UNITED STATES PATENT OFFICE

WILLIAM F. DEUTSCHER, OF NEW YORK, N. Y.

AEROPLANE CONSTRUCTION

Application filed July 14, 1930. Serial No. 467,669.

This invention relates to improvements in aeroplane construction and one of the objects of the invention is to provide new and improved means whereby the efficiency of the atmospheric pressure produced by the forward movement of the plane may be more effectively utilized in the lifting of the plane and holding it aloft.

Another object of the invention is to provide new and improved means whereby due to the increased utilization of the atmospheric pressure, the area of the wings of the plane may be relatively decreased.

Another object of the invention is to construct an aeroplane such that the stability thereof is considerably increased.

Other objects of the invention will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing, wherein I have illustrated a preferred form of embodiment of my invention,

Figure 1 is a perspective view of my improved aeroplane,

Figure 2 is a front elevational view thereof,

Figure 3 is a transverse sectional view taken on the wings, said view being taken substantially on line 3-3 of Figure 2,

Figure 4 is a top plan view, partly broken away, of the upper surface of one of the wings,

Figure 5 is a perspective view, partly broken away, of one of the air current guiding vanes which are provided in the wings,

Figure 6 is a vertical sectional view taken on the line 6-6 of Figure 4.

Referring now to the drawing wherein similar reference characters refer to similar parts throughout the several views of the drawing, the reference numeral 1 denotes the fuselage of the plane which may be of conventional form. Numeral 2 indicates the driving motor and the numerals 3 and 4 denote the usual

vertical and horizontal rudders provided in aeroplane construction.

The reference numerals 5 and 6 denote the wings of the plane which are secured in the usual manner to the fuselage 1.

Referring now to the wing construction which is illustrated in Figures 3 to 6 inclusive I provide in each wing a plurality of inclined vanes 7 which are spaced apart and suitably connected to the upper and lower walls of the wing. Each of the vanes 7 project below the lower wall 8 of the wing as at 9. The projecting portions 9 which extend beneath the lower wall of each wing are preferably curved forwardly as clearly indicated in Figure 3 of the drawing. The upper ends of the vanes 7 are curved rearwardly and lie flush with the upper surface of the wing and form the upper wall 10 thereof, said ends being spaced apart to form the longitudinally extending slits 11. I found it desirable to vary the length of the projections 9 from the forward edge to the rearward edge of the wing whereby more effectively to direct the air currents between the vanes 7 as indicated by the arrows in Figure 3, said air being directed upwardly and rearwardly between the vanes 7 so as to impinge against the under surface of the curved upper ends of the vanes as also clearly indicated in Figure 3.

Extending transversely of each wing are the supporting members 11 to which the ends of the vanes are connected as shown in Figure 4 of the drawing. These transversely extending members 11 are anchored to the front and rear portions of each wing. It will be noted that the vanes provide passageways entirely through the wing from the lower wall to the upper wall thereof.

The vanes 7 in the present instance are shown as plane members extending upwardly and rearwardly from the lower wall of the wing. The particular shape of these vanes can, of course, be varied without departing from the spirit or scope of the invention.

Referring now to the fuselage construction and particularly to Figures 1 and 2 of the drawing, it will be noted that I have provided laterally projecting members 12 and 13 from the side walls 14 and 15 of the fuselage.

These projecting members extend longitudinally of the fuselage upon each side thereof and are spaced apart as shown. I also mount a member 16 on the lower wall of the fuselage 5 extending the same rearwardly as clearly shown in Figure 1, said member being disposed in parallel relation with the laterally extending members 12 and 13 of the fuselage. If desired I may provide a similar member 10 upon the top of the fuselage extending the latter in the same direction and parallel with the members 12 and 13 and 16. These members are preferably of the same general construction as the wings 5 and 6 illustrated in 15 Figures 3 to 6 inclusive and described hereinabove and are intended not only to increase the lifting power of the air currents but also to aid in stabilizing the plane.

Having thus described the construction of 20 this embodiment of my invention, it will accordingly be seen that I have provided means whereby the lifting effect of the air through which the wings of an aeroplane are forced by the motor may be more effectively utilized, 25 the air currents, it will be noted, passing entirely through the wings of the plane and impinging against the upper and rearwardly curved ends of the vanes.

The provision of the means upon the fuselage also aids in lifting the plane as well as 30 increasing its stability.

As many changes could be made in the above construction and many apparently widely different embodiments of this invention 35 could be made without departing from the scope thereof, it is intended that all matter contained in the above description or shown in the accompanying drawing shall be interpreted as illustrative and not in a limiting 40 sense.

It is also to be understood that the language used in the following claims is intended to cover all of the generic and specific features of the invention herein described, and all 45 statements of the scope of the invention, which, as a matter of language, might be said to fall therebetween.

Having thus described my invention, what I claim as new and desire to secure by Letters Patent, is:

1. In aeroplane construction, a wing having a plurality of longitudinally extending and rearwardly inclined passageways extending through the lower surface of said 55 wing and through the upper surface thereof, said passageways being defined by vanes passing through the wing, said vanes being so disposed with respect to each other at their upper ends as to form constricted slits 60 extending longitudinally of the wing, and said vanes at their lower ends extending downwardly and forwardly.

2. In aeroplane construction, a wing having a plurality of longitudinally extending and rearwardly inclined passageways ex-

tending through the lower surface of said wing and through the upper surface thereof, said passageways being defined by vanes passing through the wing, said vanes being so disposed with respect to each other at their upper ends as to form constricted slits extending longitudinally of the wing, said vanes at their lower ends extending downwardly and forwardly, and the downwardly extending projections of said vanes increasing in length from the front to the rear side of said wing.

3. In aeroplane construction a wing having a plurality of passageways extending transversally thereof, said passageways being inclined in a rearward direction from the lower to the upper surface of said wing, said passageways being defined by vanes which are curved at their upper ends in a rear direction and at their lower ends in a forward direction, and means extending transversally of the wings to which said vanes are anchored.

4. In aeroplane construction, a wing having a plurality of vertically and rearwardly disposed vanes, the upper ends of said vanes being curved in a rearward direction and the lower ends of said vanes being curved in a forward direction.

5. In aeroplane construction, a wing having a plurality of vertically and rearwardly disposed vanes, the upper ends of said vanes being curved in a rearward direction and lying flush with the upper surface of the wing, and the lower ends of said vanes being curved in a forward direction and extending below the lower surface of the wing.

6. In aeroplane construction, a wing having a plurality of vertically and rearwardly disposed vanes, the upper ends of said vanes being curved in a rearward direction and lying flush with the upper surface of the wing, and the lower ends of said vanes being curved in a forward direction and extending below the lower surface of the wing, the extending portions of said vanes increasing in length from the leading edge to the trailing edge of the wing.

7. In aeroplane construction, a wing having a plurality of vertically and rearwardly disposed vanes forming passageways therebetween, the upper ends of said vanes being curved in a rearward direction and so disposed with respect to each other as to constrict the said passageways at their upper ends, the lower ends of said vanes being curved in a forward direction.

8. In aeroplane construction, a wing having a plurality of vertically disposed vanes inclined from the vertical in a rearward direction from the lower surface of the wing to the upper surface thereof, said vanes being curved at their upper ends in a rearward direction and at their lower ends in a

- forward direction and means extending transversally of said vanes to which said vanes are anchored.
9. In aeroplane construction, a wing having a plurality of vertically disposed vanes inclined from the vertical in a rearward direction from the lower surface of the wing to the upper surface thereof, said vanes being curved rearwardly at their upper ends to lie flush with the upper surface of the wing and to form constricted slits extending longitudinally of the wing, said vanes being curved forwardly at their lower ends and extending below the lower surface of the wing.
10. In aeroplane construction, a centrally disposed fuselage having wings attached thereto and a plurality of spaced and superimposed members projecting laterally from the sides of said fuselage, said laterally projecting members having a plurality of vertically and rearwardly disposed vanes forming passageways therebetween, the upper ends of said vanes being curved in a rearward direction and the lower ends of said vanes being curved in a forward direction.
11. In aeroplane construction, a centrally disposed fuselage having wings attached thereto and a plurality of spaced and superimposed members projecting laterally from the sides of said fuselage, said laterally projecting members comprising a plurality of vertically and rearwardly disposed vanes forming passageways therebetween, the upper ends of said vanes being curved in a rearward direction and lying flush with the upper surface of the member, and the lower ends of said vanes being curved in a forward direction and extending below the lower surface of the member.
12. In aeroplane construction, a centrally disposed fuselage having wings attached thereto and a plurality of spaced and superimposed members projecting laterally from the sides of said fuselage and extending longitudinally thereof; said laterally projecting members comprising a plurality of vertically and rearwardly disposed vanes forming passageways therebetween, the upper ends of said vanes being curved in a rearward direction and so disposed with respect to each other as to constrict the said passageways at their upper ends, the lower ends of said vanes being curved in a forward direction.
13. In aeroplane construction, a centrally disposed fuselage having wings attached thereto and a plurality of spaced and superimposed members projecting laterally from the sides of said fuselage and extending longitudinally thereof, said laterally projecting members comprising a plurality of vertically and rearwardly disposed vanes, the upper ends of said vanes being curved in a rearward direction and lying flush with the upper surface of the member, the lower ends of said
- vanes being curved in a forward direction and extending below the lower surface of the member, the extending portions of said vanes increasing in length from the leading edge of the trailing edge of the member.
14. In aeroplane construction, a centrally disposed fuselage having wings attached thereto and a plurality of spaced and superimposed members projecting laterally from the sides of said fuselage, said laterally projecting members having a plurality of vertically and rearwardly disposed vanes forming passageways therebetween, the upper ends of said vanes being curved in a rearward direction and the lower ends of said vanes being curved in a forward direction and means extending transversally of said vanes to which said vanes are anchored.
